UNITED STATES PATENT OFFICE.

GEORGE HENRY WALKER, OF WORCESTER, ENGLAND, ASSIGNOR TO HEENAN & FROUDE, LIMITED, OF MANCHESTER, ENGLAND.

FLUID-COOLING APPARATUS.

1,213,042.

Specification of Letters Patent. Patented Jan. 16, 1917.

Application filed January 11, 1916. Serial No. 71,554.

To all whom it may concern:

Be it known that I, GEORGE HENRY WALKER, a British subject, residing at Worcester, county of Worcester, England, have invented certain new and useful Improvements in Fluid-Cooling Apparatus, of which the following is a specification.

This invention relates to apparatus for cooling water or air or otherwise treating gases with liquids in which the lower portion of a laminated drum comprising a plurality of sections rotates in a trough or tank in an inclosed chamber. As at present constructed the trough or tank is divided by 10 baffle plates into a number of compartments and the water enters direct into the first compartment and thence flows through the several compartments to an outlet pipe at the other end of the machine. The hot water 15 entering and the water from each compartment as it flows into the next immediately mixes with the water contained therein and is reduced to the temperature of the water 20 therein before it is taken up by the convolutions or plates of the revolving drum.

This invention is designed to direct the inflowing hot water and the water as it flows from one compartment into the next direct onto the plates on the rising side of the 25 rotor before mixing with the water in the compartment thereby raising considerably the mean temperature difference between the air passing through the annular spaces of the drum and the film of water with which it is brought into contact.

It consists essentially in constructing the apparatus with an inlet funnel so placed as to force the inflowing hot water into the spaces between the convolutions of the first 30 section of the drum on the upwardly moving side and with double baffle plates between the sections with portions thereof cut away at alternate sides to direct the partially cooled water as it leaves the first section to 35 the spaces between the convolutions of the next section of the drum on the upwardly moving side.

It will be fully described with reference to the accompanying drawings in which 40 sufficient of a cooler is shown to illustrate the invention.

Figure 1 is a longitudinal section. Fig. 2 is a plan with cover removed. Fig. 3 is an end elevation of feed end showing the inlet

funnel D. Fig. 4 is a transverse section 55 showing the baffle plate E. Fig. 5 is a transverse section showing the baffle plate F. Fig. 6 is a perspective view of a baffle plate or weir f clearly illustrating the discharging lip or flange f'.

The apparatus is constructed with a rotor A of convolutions of sheet metal wound spirally, helically, concentrically or otherwise around a central hub, a tank B divided into compartments or sections, within which the rotor or drum A rotates, said tank being provided with a cover C. At the feed end of the tank B an inlet funnel D is fitted more or less closely against the drum plates and of such a shape as to direct and force 70 the inflowing hot water into the spaces between the convolutions of the drum A over a fairly wide area on the rising side of the rotor A and before the water has an opportunity of mixing with or flowing into the 75 water contained in the tank B.

In the tank B between the different compartments into which it is divided for the sections of the rotor, two baffle plates or partitions E and F are fitted in spaced relation to form between them a water space or auxiliary compartment G. The baffle plates E and F form weirs over which the water flows from one compartment of the casing B to the next one. Both baffle plates are 80 made deeper than the water level in the tank and the plate E is made with a cut-away portion or gap e to allow the water, after having been cooled by its rotation with the rotor A, to flow into the auxiliary compartment 90 G, and the plate F is made with a cut-away portion or gap f at the opposite side of the tank to direct the water as it flows into the next compartment onto the rotor. The gap f of the baffle plate F is made with 95 a lip f' to force the water into the spaces between the convolutions of the rotor A on the rising side.

The hot water as it enters the tank B is taken up by the rotor A and considerably 100 cooled by the air before mixing with the cooler water in the tank, the temperature difference between the inflowing water and the air being much greater; and as the water flows through the tank from compartment 105 to compartment over the different sections of the rotor A, it will flow out of the first compartment at the point near to where the

plates of the rotor or cooling drum A re-enter the water and will be delivered to the next compartment at a point near to where the plates of the rotor leave the water, and 5 will flow or find its way onto the plates of the rotor, being again considerably further cooled before mixing with the water in the next compartment and so on through the machine similar baffle plates or weirs being introduced between the second and third sections 10 and each succeeding section of the machine. By this construction the first or end compartment of the trough or tank is closed by the plate E against the direct or straight 15 flow of hot water which might otherwise short-circuit or flow direct from the funnel D to the second section without having been subjected to the cooling action of the rotor, the water then flows over the gap e in the 20 plate E into the auxiliary compartment G from which it is directed by the gap f in the plate F onto the cooling surfaces of the next section of the rotor A thereby preventing any portion of the water flowing through 25 the machine from compartment to compartment without being cooled.

What I claim as my invention and desire to protect by Letters Patent is:—

1. A cooler, comprising a plurality of 30 liquid containing compartments, a rotor in each of said compartments, and means for delivering liquid from one compartment at a point adjacent to where the rotor in said compartment enters the liquid therein, to 35 the adjacent compartment at a point adjacent to where the rotor in the latter compartment emerges from the liquid therein.

2. In a cooler, a tank divided into compartments, a rotor divided into sections, one 40 in each compartment, and means to direct the flowing water into each compartment of the tank adjacent to the rising side of the rotor and to direct the flowing water out

of the compartment adjacent to the falling side of the rotor.

3. In a cooler, a tank divided into liquid containing compartments, a rotor divided into sections, one in each compartment, baffle plates arranged in the tank, and means to direct the flow of the liquid into each 50 compartment at the side at which the plates of the rotor emerge from the water and the flow of the water out of each compartment at the side at which the plates of the rotor re-enter the water in the tank.

4. A cooler comprising a tank, weir plates arranged in pairs therein, the tank having compartments between adjoining pairs of said plates, each weir plate having a portion of its upper edge cut away, the plates of 60 each pair being spaced and having the said cut-away portions at relatively opposite ends thereof for directing liquid to flow from one compartment at an end opposite to where it enters the succeeding compartment.

5. In a cooler, a tank, partitions in said tank dividing the latter into compartments, each partition comprising a plurality of weir plates arranged in spaced relation, each weir plate having portions of its upper edge 70 cut away, the adjacent plates of each partition having said cut-away portions at relatively opposite ends for permitting the liquid to flow out of one compartment along the space between said plates and into the next 75 compartment, substantially as and for the purpose set forth.

Dated this 14th day of December, 1915.

In testimony whereof I have hereunto set my hand in presence of two subscribing 80 witnesses.

GEORGE HENRY WALKER.
